AIRPLANE KITE

Dominic L. Waldoek, Highland Park, Mich.

Application August 12, 1937, Serial No. 158,700

5 Claims. (Cl. 244—154)

This invention relates to improvements in airplane kites. It is an object of the invention to provide an airplane kite for use as a child's toy, which will remain substantially horizontal in the air, when there is sufficient wind to support it, even if it is being pulled downward by a string attached to it.

Another object of the invention is to provide an airplane kite wherein a special wing structure is provided which is both cheap and relatively simple to manufacture, and which retains the kite in a horizontal position in the air.

A further object of the invention is to provide such an airplane kite wherein the wing structure, the body, the horizontal member and the tail pieces may be packed separately in a box and the kite assembled by any child of ordinary intelligence.

Having thus briefly stated some of the major objects and advantages of the invention I will now proceed to describe an embodiment thereof with the aid of the accompanying drawing, in which:

Figure 1 illustrates a side view of the invention. Figure 2 is a front view thereof taken on the line 2—2 of Figure 1.

Figure 3 is a plan view.

Figure 4 is an enlarged section on the line 4—4 of Figure 1, and

Figure 5 is a section on the line 5—5 of Figure 4.

Referring to the drawing, 1 designates a body portion, preferably formed of thin wood arranged vertically, having a horizontal lower margin, and a downwardly and rearwardly inclined upper margin. Secured to the lower margin of the body 1, preferably by adhesive, and projecting rearwardly therefrom, is a horizontal member 2 the rear extremity of which is split vertically at 2a to receive the upper extremity of a depending tail piece 3. 4 denotes a suitable tie, formed of string or other preferred material, holding the split portions 2a together to cause them to frictionally engage the said tail piece 3. The upper tail portion 5, which is horizontally disposed, rests intermediately of its width upon the member 2 above the tail piece 3, and is secured in place by suitable adhesive.

In order to render the joint between the body 1 and the member 2 more secure I usually employ a plurality of pieces of flexible material 6 coated with adhesive. These, when in position, are substantially U-shaped, their extremities being attached to opposite sides of the body 1, and their central portions being folded beneath the member 2. The front extremity of the mem-

ber 2 is preferably substantially semi-circular in elevation, and extending forwardly therefrom is a spindle 7 upon which a propeller 8 is mounted for rotation.

The wing structure 10 is so designed that it will support my airplane kite in a horizontal position in the air so long as there is sufficient wind even when the kite is being pulled to the ground by a string 9 suitably attached to the body 1. The wing structure is made as follows: 11 designates an annular frame which rests substantially horizontally and is usually made of wire; formed thereon intermediately of its width are two front loops 12 and two rear loops 13. From Figure 2 it will be clearly seen that both sides of the frame 11 extend outwardly and upwardly from the center which rests upon the body 1. The two front loops 12 and the two rear loops 13 are arranged equidistant from the longitudinal center of the frame 11. U-shaped clips 14 and 15 support the underside of the body 1 and their sides extend upwardly adjacent the sides of the said body. The ends of the clip 14 each engage one of the loops 12 and the ends of the clip 15 are secured to the loops 13. The joints between the ends of the clips and the loops are preferably made with solder after passing the former through the latter. The body 1 is suitably held relative to the clips as shown in Figure 5 wherein a ring 16 passes through the body 1 and encircles both sides of the clip 14 intermediately of its height.

17 designates a vertically disposed annular reinforcement which extends the full width of the wing structure substantially across its transverse center line. The upper portion of the annular reinforcement 17 lies in Figure 2 in the same plane as the frame 11 except for a short distance across the longitudinal center line of the structure where the reinforcement extends above the frame 11. From both the lateral extremities of the upper portions of the reinforcement the latter is downwardly flexed as shown at 17a in Figure 2. Formed integral with the lower portion 17a are loops 18 to engage opposite extremities of a clip 19 which passes around the body 1 between the loops 12 and 13.

Extending from the front to the rear of the frame 11 and parallel with the body 1 are a plurality of annular bows 20 having their upper sides flat and soldered or otherwise secured to the front and rear of the frame 11 at their front and rear extremities. Intermediately of their length the upper sides of these bows pass immediately beneath and are soldered or otherwise secured to the upper side of the transverse reinforcement 17.

17. The lower portions 20a of the bows are downwardly flexed towards their centers where they are soldered to the lower side 17a of the reinforcement. 21 indicates spacers which extend downwardly from the upper to the lower sides of the annular bows in alignment with the reinforcement 17.

The wing structure is completed by a flexible covering 23, such as paper, the annular margin of 10 which is adhesively secured to the annular frame 11. This covering bears against the lower side of the transverse reinforcement 17 and also against the lower sides of the bows 20.

It will be noted from the curvature of the lower 15 side 17a of the reinforcement and also of the lower sides of the bows 20 that a pocket 24 of outwardly increasing depth is formed on each side of the wing structure. The pockets thus formed provide support for my airplane kite and 20 insure it remaining horizontal under practically all conditions so long as there is sufficient breeze to support it in the air.

While in the foregoing the preferred embodiment of the invention has been described and 25 shown, it is understood that the construction is susceptible to such alterations and modifications as fall within the scope of the appended claims.

What I claim is:

1. In an airplane kite, a body adapted to have 30 a string secured thereto, a member projecting rearwardly therefrom, a tail carried by said member, and a wing structure comprising an annular frame secured substantially horizontally to said body and projecting laterally on both 35 sides thereof, a vertically disposed annular reinforcement supported by both lateral extremities of said frame and having its lower side projecting beneath the latter, annular bows each secured to the front and rear of said frame, the upper 40 portion of each bow lying in horizontal alignment with the frame to brace the latter and the lower portion of each bow extending downwardly and inwardly and being connected to the lower side of said reinforcement, and a covering the 45 periphery of which is secured to the annular frame and bearing intermediately against the underside of said bows and said reinforcement.

2. In an airplane kite, the combination set forth in claim 1, wherein spacers extend between the upper and lower portions of the bows in alignment with the upper and lower sides of the reinforcement to strengthen both the bows and 5 the reinforcement.

3. In an airplane kite, a body adapted to have a string attached thereto, said body consisting of a thin vertically disposed element, a member projecting rearwardly from the body, a tail supported by said member, a wing structure resting on said body, said structure including a substantially horizontally disposed annular wire frame around its periphery, and U-clips extending beneath the body and upwardly adjacent both sides 15 thereof, the ends of the clips being secured to said frame.

4. In an airplane kite, a body, a member projecting rearwardly therefrom, a tail carried by said member, and a wing structure comprising 20 an annular frame, means securing said frame on said body, a reinforcement secured to said frame, and a flexible covering having its periphery secured to the frame and bearing against the underside of the reinforcement, the latter being 25 shaped whereby the upper side of the covering is held concave in section longitudinally of the body and the depth of the concavity decreases from the lateral extremities of the wing structure towards the body, said wing structure extending a 30 substantially equal distance on both sides of said body.

5. In an airplane kite, a body adapted to have a string attached thereto, a member projecting rearwardly from the body, a tail carried by said 35 member, and a wing structure which projects laterally on both sides of said body and is secured thereon, said wing structure being concave in section longitudinally of the kite on its upper side adjacent both lateral extremities of said 40 structure, the depth of said concavities diminishing towards the longitudinal center line of the kite.
